FUEL-FEEDING APPARATUS FOR INTERNAL-COMBUSTION ENGINES.

1,188,953.

Specification of Letters Patent. Patented June 27, 1916.

Application filed May 16, 1914. Serial No. 839,158.

To all whom it may concern:

Be it known that I, SIMON LAKE, a citizen of the United States, residing at Milford, in the county of New Haven and State 5 of Connecticut, have invented certain new and useful Improvements in Fuel-Feeding Apparatus for Internal-Combustion Engines, of which the following is a specification.

The invention relates particularly to certain improvements in the types of engines shown and described in my copending application filed April 27th, 1912, Serial No. 693,701, (now Patent No. 1,096,730, dated May 12, 1914), June 4, 1912, Serial No. 15 701,564, and March 7, 1914, Serial No. 823,172.

One object of the invention is to provide a simple and efficient fuel feeding apparatus for high and low compression internal combustion engines by which low grades of oil or heavy oils may be injected into the combustion chambers of the cylinders in accurately measured quantities and in a thoroughly atomized condition thus insuring complete combustion of the fuel and the consequent uniform working of the engine when running at high or low speeds, the operation of the apparatus being such that the oil is first pumped into a high pressure 30 tank or reservoir from which it is driven under air pressure into an injector and thence into a mixing chamber in the casing of the inlet valve where it is mixed with the injecting air and converted into gas or a gaseous vapor before being admitted to the cylinder, means being provided for automatically cutting off the supply of oil to the pressure tank so that a uniform pressure is maintained therein for forcing the oil into 40 the injector.

A further object of the invention is to provide for the mixing of a higher grade of oil with the heavy oil and for treating the air used for injecting the fuel into the cylinder so as to enrich and insure complete combustion of the fuel when injected into the cylinder.

The invention consists in the peculiar and novel construction, combination and arrangement of parts as will be hereinafter fully described and then claimed.

In the drawings, illustrating the invention, in the several figures of which like parts are similarly designated, Figure 1 is 55 a front view of the upper end of the engine cylinder of an internal combustion en-

gine embodying my invention. Fig. 2 is a sectional elevation of the fuel pump. Fig. 3 is a transverse section drawn through the upper end of the cylinder and the upper end of the power piston. Fig. 4 is a vertical section of the inlet valve casing. Fig. 5 is a horizontal section drawn on the line *b*—*b* of Fig. 4. Fig. 6 is a detail transverse section drawn on a larger scale on the line *c*—*c* of Fig. 4. Fig. 7 is a front view of the injector and the outer end of the lever for operating the several valves of the apparatus. Fig. 8 is a vertical transverse section drawn on the line *d*—*d* of Fig. 7. Fig. 9 is a transverse section drawn on the line *e*—*e* of Fig. 7. Fig. 10 is a horizontal section drawn on the line *f*—*f* of Fig. 8. Fig. 11 is a horizontal section drawn on the line *g*—*g* of Figs. 7 and 8. Fig. 12 is a diagrammatic view illustrating the treating of the oil and air before being injected into the cylinder.

1 designates the power cylinder of the engine in the head 2 of which is mounted a 80 valve casing 3 having a needle-valve 4 which controls the admission of the fuel to the combustion chamber of the engine. The valve casing is provided at its lower end with a mixing and gas generating chamber 5 into 85 which opens an air passage 6 to which is connected an air supply pipe 6' extending from a suitable source of high pressure air supply (not shown), the air being employed for forcing the fuel into the combustion chamber and for uniting with the fuel to provide a combustible mixture. The casing 3 is also provided with an oil passage 7 to which is connected a pipe 8 extending from an injector 9, hereinafter fully described. The lower end of the passage 7 is formed with a valve seat for a spring seated inwardly opening check-valve 10 which controls the back flow of the air, oil or gaseous vapor through the passage 7, the upper end 100 of the stem of the valve being connected by a coil spring 11 carried by a washer held in the upper end of the vertical bore of the passage 7, the said upper end being closed by a screw plug 12, best shown in Fig. 4. 105

A bracket 10' is connected to the top of the chamber 5 and extended across the valve 10 to form a stop to limit the downward movement of the valve when the oil is forced into the chamber 5. The lower end of the chamber 5 is closed by a plug 13 which is screwed into the lower end of the casing and

is provided with a centrally disposed outlet port 14 which opens into the combustion chamber 1' of the cylinder, and surrounding the upper end of the port is a valve seat for 5 the needle-valve 4 the stem of which extends upwardly through the casing and through a stuffing box 16 formed therein, and has its upper end connected to an operating lever 17 pivoted at its rear end to a bracket 18 10 mounted on the top of the cylinder head 2 and having its forward end arranged for engagement with a lifting rod 19, similar to the arrangement shown in my aforesaid co-pending application, Serial No. 701,564, and 15 as will be hereinafter further described. The valve 4 is normally held to its seat by a flat spring 20 carried by studs 21 extending upwardly from the top of the casing 3. The plug 13 is formed with a sleeve 22 20 which surrounds the lower end of the valve stem and immediately above the valve seat the said sleeve is formed with an annular recess 23 which communicates with the generating and mixing chamber 5 through a 25 series of ports 24 arranged in and around the lower end of the sleeve. 25 designates a series of disks, each having a plurality of small perforations which are arranged in staggered relation to the perforations of its 30 adjacent disks and which are designed to deflect the course of the oil as it passes through the chamber 5 so as to break it up and cause it to be more readily converted into a gaseous vapor or spray as the fuel passes 35 through the chamber 5. The disks 25 are held in place by a nut 27 screwed upon the sleeve 22 as shown in Fig. 4. In order that the lower end of the valve casing 3 may be thoroughly heated by the heat of the combustion chamber whereby to instantly convert the fuel oil as it passes through the chamber 5 into gas or a gaseous vapor; I enlarge the lower end of the bore in the head of the cylinder through which the valve casing 40 passes as shown at 26, Fig. 3, so that the walls of the chamber may be exposed to the heat of the combustion chamber as will be well understood.

The piston 28 is provided with a centrally 50 disposed plug 29 of tungsten which is screwed into the head of the piston and has its upper end formed with a slight crown so as to deflect the oil, vapor or gas as it enters the combustion chamber, it being understood 55 that as the fuel passes through the inlet port 14 it will strike against the top of the plug and thus be sprayed into all parts of the combustion chamber and thus be more readily ignited by the heat of the highly 60 compressed air as in high compression engines, or by the sparking plugs as in low compression engines.

Like the construction shown in my aforesaid application Serial No. 693,701, the present engine is of the self-starting reversible

type, and starting air is supplied to the cylinder through a pipe 30 extending from a suitable source of supply (not shown), the passage of the air through the pipe being controlled by a lifting valve 31 which is 70 operated by a lifting rod 32 carried by a vertically movable cylindrical member 33 operatively held in a bearing 34 formed on a bracket 35 secured to the face plate of the power cylinder. The lower end of the cylindrical member is formed with a disk 36 which is normally held in contact with lifting pawls 37 carried by a rocker-arm 38 journaled on a stud bolt extending from the bracket 35, and having its lower end designed 75 for engagement by push cams 39 carried by a reciprocating tubular shaft 40 mounted on a shaft 41 rotatably held in bearings 42 extending from the cylinder 1. The upper end of the bearing 34 is formed with an 80 annular recess in which operates the lower end of a collar 43 carried by the upper end of the cylindrical member 33 providing a dash-pot to cushion the seating of the several parts of the apparatus.

46 designates a rocker-arm journaled on a stud bolt which also extends from the bracket 35 and has its lower end positioned for engagement by cams 47 mounted on the tubular shaft 40, and like the arm 38, the 95 arm 46 carries pawls 48 against which normally seats a disk 49 formed upon the lower end of a cylindrical member 50 which is operatively held in a bearing 50' formed on the bracket 35, and from which extends the 100 lifting rod 19 for operating the valve lever 17. The rocker arms 38 and 46 are held in vertical position when not engaged by their co-acting push cams, by flat springs 45 carried by the bracket 35 and which are arranged to lie against the opposite sides of short pins extending from the lower ends of the vertical members of the arms, and the pawls 37 and 48 are tripped from engagement with their cams so as to time the seating of the valves by trip pins 44 as shown. It is obvious that by adjusting the pins upwardly or downwardly the tripping of the pawls from their cams may be regulated to 110 control the seating of the valves to thus regulate the admission of the starting air and fuel into the cylinder and the gas generating chamber, respectively.

The rod 19 serves the double purpose of 115 operating the valve lever 17 and of controlling the passage of the fuel oil to the chamber 5 of the valve casing 3, and as shown, the said rod operates through the injector 9 as I will now describe. The injector is provided with an oil passage 53 to which is connected an oil supply pipe 54' extending from a tank or reservoir 212 in which the oil is held under air pressure and the oil is supplied to the tank by a pump 55 as will be presently explained. Air under the required pressure 120

is supplied to the tank through a pipe 212' extending from any suitable source of supply (not shown). Diametrically opposite the passage 53 is an oil passage 56 which is 5 designed to be thrown into communication with the passage 53 through ports 57 arranged in the walls of the injector and which open into the bore through which the rod 19 operates, and through ports 58 10 formed in said rod (Figs. 8 and 10). The upper end of the passage 56 terminates in a horizontal branch 56' which communicates with a vertical passage 59 having a valve seat adjacent to its lower end against which 15 operates a spring seated check-valve 60. The upper end of the passage 59 opens into a horizontal passage 61 which communicates with a vertical passage 62 having its lower end opening into an oil holding and measuring cylinder 63 formed horizontally in a branch 63' cast integral with the injector 9 and in which operates a spring actuated plunger piston 64 which is supported at its outer end in a bore formed in a head 65 carried at the outer end of parallelly arranged rods 66 extending from bosses formed on the sides of the branch 63' of the injector. The plunger piston carries an arm 67 slidably held on the rods 66 and between which 20 and the head 65 is interposed a spring 68 which serves to move the piston forwardly in the cylinder to force the oil therefrom as will be explained later on. The upper end of the passage 62 opens into a passage 62' 25 which extends through a nipple formed on the injector and to which the pipe 8 leading to the valve casing 3 is connected. A needle-valve 69 controls the outlet from the passage 62 and has its stem extended upwardly through a stuffing box 70 formed in the upper end of a vertical extension cast with the injector and the upper end of the stem is formed with an eye to receive a pin 71 carried by ears depending from the lower 30 side of the lever 17 adjacent to its outer end. The valve 69 is normally held to its seat by a spring 72 which is connected at its upper end to the lever 17 and at its lower end to a plug 73 screwed into the upper end of the 35 passage 59.

The lifting rod 19 is formed with a recess to receive a key 51' carried by a stuffing-box sleeve 74 through which the rod passes, and which serves to prevent rotation of the said 40 rod and the consequent shifting of the ports 57 and 58 out of alinement.

As in my aforesaid application Serial No. 823,172, the tubular shaft 40 is reciprocated on the shaft 41 by an elbow lever operatively 45 connected to the crank-shaft of the engine and in my present invention I provide the said lever 74 with a downwardly extending arm 75 which is connected by a link 76 to the piston 55' of the fuel pump 55. By this arrangement it will be understood, that on

each movement of the elbow-lever to reciprocate the tubular shaft 40 to cause the cams to engage and rock the arm 46, fuel will be first drawn into the pump through the pipe 77, and on the next stroke the fuel thus 50 drawn in will be forced through the pipe 54 into the pressure tank or reservoir 212 from which it is forced through the passages in the injector 9, past the valve 60 into the cylinder 63, the pressure in the tank serving 55 to force the oil in the cylinder until the plunger piston is pushed backwardly to the end of its stroke and wherein it is held until the needle-valve 69 is lifted from its seat when the spring 68 will force the piston forwardly in its cylinder thus forcing the oil into the chamber 5 of the valve casing against the pressure of air therein as will be best understood from the general description of the operation of the apparatus. The 60 oil is supplied to the pump through the pipe 77 which extends from a suitable source of supply, and the pump 55 is provided with a suction valve 77' and with an outlet check valve 54" in the usual manner. 90

The operation of the engine so far as described is as follows:—It may be first stated that in practice a greater pressure is maintained against the oil in the tank 212 than that of the air in the generating chamber 95 5 of the valve-casing which is employed for forcing the fuel into the combustion chamber of the engine, so that, when the injector is open to communication with the said chamber the oil from the cylinder 63 will 100 be readily forced into the said chamber 5. We will assume that the engine is running on fuel oil. As the elbow lever 74 is operated the pump will be set in motion to first draw in a charge of oil and on the next 105 stroke to pump it through the pipe 54 into the pressure tank 212 against the air pressure therein. Now as the cam shaft 40 is reciprocated, depending, of course, on the direction of rotation of the power shaft, one 110 of the cams 47 will engage and rock the arm 46 which first elevates the lifting rod 19 sufficiently to throw the ports 58 therein out of communication with the ports 57 of the injector 9, thus cutting off the communication 115 between the pressure tank 212 and the oil cylinder 63, then on a continued upward movement of the lifting rod the latter will engage and lift the outer end of the lever 17 to first lift the valve 69 to establish 120 communication between the said oil cylinder and the chamber 5 of the valve casing and the moment the valve 69 is operated the plunger piston 64 will be forced forwardly 125 in its cylinder by the spring 68 thus forcing the oil into the generating chamber 5 against the air pressure therein and the oil is thoroughly mixed with said air and through the heat of the chamber it is converted into gas or a gaseous vapor. Then, 130

on a continued upward movement of the lifting rod 19, the lever 17 will be further elevated and the needle-valve 4 lifted from its seat so that the oil, gas or gaseous vapor will be forced into the combustion chamber 5 by and along with the air in said chamber 5. As the fuel passes through the chamber 5, assuming that the oil has not been generated into vapor, it will, in its passage through the perforations of the plates 25, be broken up before reaching the outlet 14 and consequently will be sprayed into the cylinder in a thoroughly atomized condition, and as before stated, as the fuel enters the combustion chamber it will strike against the plug 29 and be deflected into all parts of the chamber. It will, of course, be understood that sufficient play is furnished between the connections of the valves with the lever 17 to permit of their operation in the sequence described.

In order to regulate the quantities of fuel injected into the cylinder to thus regulate the speed of the engine, I provide the following arrangement: Mounted in a bearing 93 formed upon the extension 63' of the casting 9, and in a bearing 94 formed upon the head 2 of the cylinder, is a shaft 95 having a threaded section 96 on which operates a nut 97 having an upwardly extending lip 98 which bears against the forward side of the cross-arm 67 of the plunger piston 64, so that, should the shaft 95 be rotated to adjust the nut rearwardly, the plunger piston will likewise be moved against the tension of its spring and its forward movement arrested when it is moved forwardly in its cylinder, and before it reaches the end of its stroke. By this arrangement, when the pressure tank 212 is in communication with the oil cylinder 63 and although sufficient oil will be forced into the cylinder to completely fill it, the forward or pumping stroke of the piston will be arrested before it reaches its extreme forward movement and in consequence a smaller amount of fuel will be forced into the chamber 5 than would be the case were the piston permitted to travel the full length of its stroke. The rear face 50 of the lip 98 is formed with a recess to receive a washer 99, of raw hide or other suitable material, to reduce the noise incident to the seating of the arm 67 against the lip. To indicate the stroke of the plunger piston, 55 and to determine the amount of fuel injected into the chamber 5, I provide the cross arm 67 with an upwardly extending bar 100 to the upper end of which is connected the rear end of a link 101 having its forward end 60 connected to an indicator hand 102 which is pivotally mounted at its lower end to a plate 103 extending upwardly from the branch 63' of the injector and having a dial 104 over which the free end of the indicator hand operates. By this construction, when

the nut 97 is adjusted rearwardly on the shaft 95 to move the arm 67 rearwardly against the tension of its spring, the indicator hand 102 will be moved over the dial to the position, for instance, as shown in dotted lines in Fig. 7, to thus indicate that the piston will be given only one half of a stroke, and, in consequence, only one half of the full charge of fuel will be injected into the chamber 5.

It is obvious that when communication between the injector 9 and the tank or reservoir 212 is cut off as when starting the engine when the fuel operating cams are out of co-acting position with their rocker arm, 70 and also when the engine is running at reduced speeds and on reduced charges of fuel, provision must be made to prevent the continuous pumping of the fuel-oil into the tank or reservoir since the pumping of more fuel into the tank than is withdrawn therefrom would unnecessarily increase the pressure in the tank, and to this end I extend a pin 77" through the lower end of the pump in alinement with the stem of the suction valve 77' (Fig. 2), and having its upper end spaced from the lower end of the valve stem and its lower end resting against the top plate of a diaphragm 105 mounted below the pump, and communicating with the chamber 95 of the pump is a pipe 106 which extends from the pipe 54. By this arrangement the diaphragm is set to hold against a pressure equal to that of the pressure tank 212 and should excess quantities of oil be pumped 100 into the tank and the pressure in the tank thereby increased, additional quantities of oil will also be forced into the chamber of the diaphragm causing the latter to expand and thus lift the pin 77" to raise and hold 105 the suction valve 77' open so that, on the compression or pumping stroke of the pump piston, the oil will be forced back through the open valve and the pipe 77 into the supply tank instead of being forced into the 110 tank 212, the pressure on the oil in the pipe 54 then holding the check valve 54" to its seat. It will be understood, that the moment enough oil has been drawn from the tank 212 to reduce the pressure to that at 115 which the diaphragm is set, the latter will be contracted to allow the suction valve to be seated and the pump to function in the normal manner. A light spring (Fig. 1), is employed for holding the pin 77" against 120 the diaphragm.

As is well known, some grades of fuel oils are of such a heavy quality that they require a more volatile fuel, such as gasoline or kerosene for instance, to be mixed with them to render the heavier oils readily combustible and in such cases I purpose using two pressure tanks and a supply tank for the light fuel as shown in Fig. 12, and which I shall now describe.

200 designates a double plunger pump to the suction end of one cylinder 200' of which is connected a supply pipe 201 leading from a suitable supply source, and to the outlet from the pump is connected a pipe 202 extending to a pressure tank 203 from the top of which extends an air or gas pipe 204 which leads to the passage 6 of the valve casing 3. The supply pipe 201 is provided with a check-valve 205 and between the check-valve and the pump the supply pipe is connected by a pipe 206 extending from a gasoline tank 207, the pipe 206 being provided with a drip-cock 208 and a sight-feed glass 209 whereby to regulate the quantity of gasoline or other light oil to be mixed with the heavier oil. The suction end of the cylinder 200' of the pump is connected by a pipe 210 with the lower end of the tank 203, and the outlet from the cylinder 200' is connected by a pipe 211 with the pressure tank 212, and from the tank 212 extends a pipe 213 which leads to the oil passage 53 of the fuel injector 9, which pipe 213 corresponds with the pipe 54' in Fig. 1.

Air under pressure is supplied to the tank 203 through a pipe 203'' extending from a suitable source of supply (not shown), and in order to maintain a uniform pressure in the tank 203 as well as in the tank 212, the suction valves of the pumps 200' and 200'' have their stems 214 and 214' respectively, extended through the lower ends of the pumps and held in engagement with levers 215 and 215' respectively, which are pivotally connected at one end to a common bracket extending from the pump. The free end of the lever 215 is connected by a connecting rod 216 with the free end of a lever 217 carried at the outer end of a rock-shaft 218 journaled in and extending through one side of the tank 203, and to the inner end of the said shaft is connected a float 219 which floats on the top of oil within the tank. By this arrangement, should a greater quantity of oil be pumped into the tank than is drawn therefrom during the operation of the engine (as would occur when the engine is running at reduced speeds), and the oil is raised above a predetermined level, the float will rise with the oil and thus rock the shaft 218 and elevate the outer end of the lever 217 and thus lift the lever 215 to lift the suction valve of the cylinder 200' from its seat so that on the pumping stroke of the piston working in the cylinder 200' the oil will be forced back through the pipe 201, but as the check valve 205 will prevent the oil being forced back into the reservoir, I provide the pipe 206, leading from the pipe 201, with an air chamber 225 so that the oil in the pipe will be pumped from and back into the air chamber, thus preventing the clogging of the pump or the bursting of the pipes 201 and 206.

The free end of the lever 215' is held in engagement with the top plate of a diaphragm 220, the chamber of which is connected through a pipe 221 with the pipe 213 leading from the tank 212 to the injector 9, so that should excessive pressures be put upon the oil in the said tank and in the pipe 213, additional quantities of oil will be forced into the chamber of the diaphragm causing it to expand in the same manner as that described with reference to the diaphragm 205, to thus rock the lever 215' to lift the suction valve of the pump 200'' so that the oil drawn into the pump will be forced back into the tank 212 as will be understood.

With the use of the two pressure tanks the oil will be first pumped into the tank 203 against a pressure, we will say, of 800 pounds per square inch, and from the tank 203, it is pumped into the tank 212 against a greater pressure, for example, 1000 pounds per square inch, and from the tank 212 the oil is supplied to the injector in the same manner as that described with reference to the tank 212 shown in Fig. 1. With the use of poor grades of oils, or oils of such refractory nature that they are not readily ignited when injected into the cylinder of the engine, and which require a more volatile fuel to be mixed with it to afford ready combustion, I then open the drip-cock controlling the outlet from the tank 207 so that the required quantities of light fuel may flow into the pipe 201 to be mixed with the heavy oil as it is being pumped into the tank 203.

It will be understood, that when the lighter fuel is turned into the supply pipe 201, the pump will draw from the main supply the regular charges of heavy oil less the amount of that supplied from the tank 207. With the use of the pressure tank 203 I purpose passing the air that is used to force the fuel into the combustion chamber through the said tank so that the air will be impregnated with the gas contained in the volatile fuel, the richness of the gaseous mixture depending, of course, on the amount of volatile fuel that is pumped into the tank. As the air is thus mixed with a more inflammable material than is the heavier oil which is pumped from the bottom of the tank 203, it will be conceived that, when the gaseous air is let into the combustion chamber along with the heavy oil or the gaseous vapor generated in the chamber 5 of the valve casing, a more readily combustible or ignitable mixture will be produced.

As shown, the air is supplied to the tank 203 through a pipe 203' which is extended through the bottom of the tank and immediately above the top of the pipe is arranged a perforated partition 223' which serves to break up the solid column of air as it enters

the tank so that it will be thoroughly mixed with the gas that is contained in the fuel as it passes up through the liquid.

Although my invention relates particularly to high compression engines in which the fuel is ignited through the heat of the highly compressed air in the combustion chamber, I do not want it understood that I limit myself to such types of engines as the apparatus may be used with equal effectiveness on engines using sparking plugs to ignite the fuel injected into the combustion chamber. With the use of sparking plugs on engines embodying my improved valve operating gear I am able to dispense with the use of timers now commonly employed.

As shown in Figs. 1 and 3, the plugs 300 are connected by wires 301 extending from a battery 302, and interposed in the wires 20 is a contact member 303, comprising a lower spring plate having its free end disposed and suitably spaced above the top of the cylindrical member 50 of the lifting rod 19 for operating the valve lever 17, and above 25 the spring plate is a fixed plate carrying an adjustable contact screw 304 which is designed to be engaged by the spring plate when the latter is bent upwardly by the cylindrical member 50 when the latter is forced 30 upwardly in the operation of the valve lever 17. By this arrangement when the rocking arm 46 is operated to lift the cylindrical member 50 the spring plate of the contact member will be forced into engagement 35 with the contact screw 304 to thus complete the circuit through the wires and to create a spark at the end of the sparking plugs 300.

What I claim is:—

1. In an internal combustion engine, a power cylinder having a valve controlled fuel inlet leading into the combustion chamber thereof, a lever for operating said valve, a fuel injector communicating with said fuel inlet, a source of fuel supply under pressure piped to said injector, means comprising a needle valve operatively connected with said lever for controlling the passage of fuel from the injector to said fuel inlet, and means for operating said inlet valve lever.

2. In an internal combustion engine, a power cylinder having a valve controlled fuel inlet leading to the combustion chamber thereof, a lever for operating said valve, a fuel injector communicating with said fuel inlet, means to supply air under pressure to said inlet, a source of fuel supply under pressure piped to said injector, means to supply fuel to the supply source, and a common means for controlling the admission of fuel to said injector and for actuating said valve operating lever.

3. In an internal combustion engine, a power cylinder having a valve controlled fuel inlet leading to the combustion cham-

ber thereof, a lever for operating said valve, a fuel injector piped to said inlet, a pair of fuel supply tanks, means for conducting fuel from one of said tanks to the other, means to supply air under pressure to one 70 of said tanks, means for conducting the air from said tank to said fuel inlet, for the purpose specified, means for conducting fuel from the other of said tanks to said injector, and means for controlling the admission of fuel to said injector and for actuating said valve operating lever to admit fuel to said combustion chamber.

4. In an internal combustion engine, a power cylinder having a valve controlled fuel inlet leading to the combustion chamber thereof, a lever for operating said valve, an injector having a fuel-oil holding cylinder piped to said fuel inlet, a source of fuel-oil supply under pressure piped to said injector, a plunger piston operating in said oil holding cylinder, a valve controlling the outlet from said oil holding cylinder and operatively connected to said valve lever, and a lifting rod for operating said valve lever, said rod operating through said injector and controlling the admission of fuel-oil to said oil holding cylinder.

5. In an internal combustion engine, a power cylinder having a fuel inlet leading into the combustion chamber thereof, a valve controlling said inlet, a lever for operating said valve, a fuel injector having a fuel-oil holding cylinder piped to said inlet and an oil passage leading thereto, a valve operatively connected to said valve lever and controlling the outlet from said oil holding cylinder, a spring actuated plunger piston working in said oil holding cylinder, a fuel-oil holding tank under pressure piped to the passage leading to said oil holding cylinder, a lifting rod for operating said valve lever, said rod operating through said injector and controlling the flow of oil through said passage, means for operating said lifting rod, and means to supply air under pressure to said fuel inlet of the power cylinder.

6. In an internal combustion engine, a power cylinder having a fuel inlet leading to the combustion chamber thereof, a valve controlling said inlet, a lever operatively connected to said valve, a fuel-oil injector piped to said inlet and having a fuel-oil holding cylinder and a supply passage leading thereto, a valve operatively connected to said lever and controlling the outlet from said oil holding cylinder, a fuel-oil holding tank under pressure piped to the oil passage of the injector, a spring actuated plunger piston operating in said oil holding cylinder, means for regulating and means for indicating the stroke of the plunger piston, means to supply air under pressure to said fuel inlet of the power cylinder, and a com- 134

mon means for operating said valve operating lever and for controlling the passage of fuel-oil through the supply passage of the injector.

5 7. In an internal combustion engine, a power cylinder having a valve controlled inlet leading to the combustion chamber thereof, a lever for operating said valve, a fuel-oil injector piped to said inlet and having
10 an oil holding cylinder and an oil passage leading thereto, a plunger piston working in said oil holding cylinder, a fuel-oil supply tank under pressure piped to said oil passage, a pump for supplying fuel oil to said
15 tank against the pressure therein, means to supply fuel oil to the pump, means for maintaining a predetermined level of the fuel oil in said tank, for the purpose specified, and a common means for controlling
20 the supply of oil to said oil holding cylinder and for operating said valve lever.

8. In an internal combustion engine, a power cylinder having a valve controlled fuel inlet leading into the combustion chamber thereof, a lever for actuating said valve, a fuel injector connected with said fuel inlet, a source of fuel supply under pressure
25

piped to said injector, means for controlling the supply of fuel to said injector, a spring actuated means for forcing the charge of fuel contained within said injector into the combustion chamber of the engine when the fuel inlet valve thereto is open and the supply to said injector is closed, and a valve in said injector connected with the means for controlling the supply of fuel to said injector to control the discharge of fuel therefrom.

9. In an internal combustion engine, a power cylinder having a valve controlled fuel inlet leading into the combustion chamber thereof, a lever for actuating said valve, a fuel injector connected with said fuel inlet, a source of fuel supply piped to said injector, and a lifting rod for actuating said lever, said rod passing through said injector and serving to cut off the supply of fuel thereto when lifted to actuate said lever.

In testimony whereof I have hereunto set my hand this 12th day of May, A. D. 1914.

SIMON LAKE.
